tion of Michigan

Application February 16, 1951, Serial No. 211,358

8 Claims. (Cl. 315—269)

1

This invention relates to a circuit for effecting synchronous energization of an electronic tube.

More specifically, this invention relates to an electrical circuit for controlling the energization of an electronic tube in which conduction through the electronic tube is always initiated at the beginning of a positive half cycle of anode voltage. One object of the present invention is the provision of an improved synchronizing circuit for an electronic tube whereby the electronic tube will conduct only full half cycles of current.

Another object of the present invention is the provision of an improved electronic tube initiating circuit operating to effect initiation of conduction through the electronic tube only at the beginning of a half cycle of positive anode voltage regardless of the point on the voltage wave at which the initiating contact may be closed.

Another object of the present invention is the provision of an energizing circuit for an electronic tube in accordance with the preceding objects, in which voltages differing in time-phase are applied to the control and shield grids of the electronic tube to effect energization of the electronic tube at a particular point on the anode voltage wave.

Other objects and features of the invention will be readily apparent to those skilled in the art from the specification and appended drawings illustrating certain preferred embodiments in which the drawing is a diagrammatic representation of an electronic welder circuit in which the present invention is incorporated.

In the drawing there is shown a pair of main supply lines 1 and 2, which are connected to a source of energy, not shown. Disposed across these supply lines is a transformer 3 having a secondary 4 which supplies a pair of conductors 5 and 6 which electrical energy. Connected across these conductors 5 and 6 is a transformer 7 having a secondary winding 8 which is of opposite polarity to the primary of transformer 7.

The secondary winding 8 is connected between the conductor 6 and a conductor 9. In series with each other, and connected between the conductors 6 and 9, are a resistor 11 and initiating contact 12. To a point between the resistor 11 and the contact 12 there is connected one terminal of a capacitor 13, the other terminal being connected through a resistor 14 to the control grid 15 of an electronic tube 16, which has an anode 17, a cathode 18, and a shield grid 19. The shield grid 19 is connected to a junction between the elements of a series cir-

5

cuit which comprises a resistor 21 and a capacitor 22, this series circuit being disposed between the conductors 5 and 9. Also connected to the conductor 9 is a resistor 23 which is electrically connected to the control grid 15 of the electronic tube 16 through the resistor 14. Also connected to the control grid 15 is one terminal of a capacitor 24, the other terminal thereof being electrically connected to cathode 18 of tube 16. Across the conductors 5 and 6 there is disposed a transformer 25 having a secondary 26 which serves to supply heat to the cathode 18 of the tube 16.

15

The anode 17 of the tube 16 is connected to the conductor 5 through a circuit which comprises a weld-no-weld switch 27, which is in series with a parallel circuit, one leg of which includes an inductor 28 and a capacitor 29; the other leg includes a relay coil 31 of an electromagnet. Energization of the relay coil 31 effects movement of a movable contact 32 into position to bridge contacts 33 in the igniter circuits of a pair of inversely paralleled ignitrons 34 and 35, which are conventionally disposed between the 20 main supply lines 1 and 2. These ignitrons serve to energize a welding transformer 36 in series with the ignitrons across the supply lines, transformer 36 having a secondary winding 37 across which a pair of welding electrodes 38 are disposed.

30

Upon connection of the main line conductors 1 and 2 to a source of electrical energy, the transformer 3 will be energized, the transformer 3 secondary winding serving to energize transformers 7 and 25, secondary 26 of the latter transformer supplying energy to heat cathode 18. With the switch 27 closed, anode voltage will be supplied to the main electrodes 17 and 18 of the tube 16. With the initiating contact 12 in the position indicated in the drawing, during those half cycles in which the anode 17 of the tube 16 is driven negative with respect to the cathode 18, current will pass through resistor 11, capacitor 13, and the path between the control grid 15 and the cathode 18 of tube 16 to charge capacitor 13. This current flow through the control grid when the anode is negative is due, of course, to the fact that secondary 8 is of a polarity opposite to that of the secondary 4. This charge on capacitor 13 establishes a D. C. voltage in the control grid circuit of the tube 16 which provides a voltage between the control grid 15 and the cathode 18 of tube 16 which is negative at all times, except for short periods during which 40 anode 17 is substantially negative with respect

to the cathode 18, so that tube 16 will not conduct. During these aforementioned short periods, the charge upon capacitor 13 is reestablished by control grid conduction of tube 16.

To the shield grid 19 of the tube 16, there is applied the voltage across capacitor 22 which slightly lags the voltage of the secondary winding 8. The shield grid 19 conducts current during the positive half cycles of voltage applied thereto, and by virtue of the phase displacement between the shield grid voltage and the voltage of secondary winding 8, the shield grid will remain positive for a short period during which the anode 17 goes positive, the shield grid 19 going substantially negative after this short period and remaining so until after the anode 17 goes negative.

When the initiating contact 12 is closed, further recharging of the capacitor 13 is prevented, the capacitor 13 thereby discharging through resistors 11 and 23, the voltage at the control grid 15 of tube 16 during this discharging period being comprised of the decaying voltage of the capacitor 13, upon which is superimposed a small A. C. voltage due to current flow through resistors 23 and 14 and capacitor 24. This A. C. voltage component lags the voltage of the secondary winding 8 and, therefore, tends to maintain the control grid 15 positive at the beginning of a positive half cycle of anode 17 voltage. As the voltage upon capacitor 13 is dissipated, tube 16, therefore, will begin to fire only during those periods in which the shield grid and the anode are both positive, these moments occurring only at the beginning of a positive half cycle of anode voltage. If conduction of tube 16 is not initiated at the beginning of one positive half cycle, the shield grid voltage, which is substantially negative during the remainder of that half cycle, will prevent firing of the tube until the beginning of the succeeding positive half cycle of anode voltage, regardless of the fact that the capacitor 13 voltage may be dissipated, and the control grid lose its negative bias, during said one positive half cycle. Assuming that the switch 27 is closed, tube 16 will then begin to conduct current. This current will effect the energization of the coil 31 which will, after a predetermined period, effect closure of the movable contactor 32 upon the fixed contacts 33. One relay of this type which is designed to provide substantially transient free weld current initiation by effecting closure of the contacts at approximately the normal current zero for the associated welder is shown and described in the copending application of Robert C. Mierendorf and Ernest G. Anger, entitled Electro-Magnetic Relay, Serial No. 152,594, filed March 29, 1950. This relay will close the contacts about 240° after the initiation of current flow through the energizing coil. It should be noted that this closure therefore occurs during the half cycle which follows the first conducting half cycle of tube 16.

Upon closure of the contacts 33, current will flow from the main power lines to effect ignition of the ignitron having positive anode voltage, current then flowing from the positive power line through the ignitron to energize welding transformer 36, the secondary 37 thereof effecting current flow through the welding electrodes 38 and the work associated therewith. Ignitrons 34 and 35 will continue to conduct successive half cycles of current until such time as the movable contactor 32 is no longer bridging the fixed contacts 33.

The circuit paralleling the relay coil 31 is so

designed as to maintain the coil 31 energized during those half cycles of non-conduction of tube 16 which follow conducting half cycles. Upon opening of the initiating switch 12, a charge will be reestablished on capacitor 13 and operation of the tube 16 will be interrupted. During the first half cycle of non-conduction of tube 16, capacitor 29 will, in the conventional manner, be discharged through relay coil 31 to maintain its energization. Upon the second half cycle of non-conduction, the inductor 28, which is chosen to have a value such that the combination of the inductor 28 and the capacitor 29 are in resonance, will cause a rapid reversal of current flow through the relay coil 31 and consequent rapid deenergization thereof. The contacts 33 will therefore always be opened during the second half cycle which follows a conducting half cycle of tube 16. This resonated circuit is described and claimed in the copending application of Ernest G. Anger entitled Electric Control Circuit, Serial No. 148,190, filed March 7, 1950.

It will readily appear that tube 16 may begin to conduct only upon the beginning of a positive half cycle of anode voltage and therefore only full half cycles of current will pass through the tube. Current flow through relay coil 31 will therefore occur only in full half cycles. Furthermore, as contacts 33 are always closed during the first half cycle following a conducting half cycle of tube 16, and as contacts 33 are always opened during the second half cycle following such conduction, weld current flow will therefore always be initiated in half cycles of the same polarity and will be interrupted during half cycles of opposite polarity. Furthermore, it is obvious that while the feature of the present invention which provides for synchronous start of current flow through tube 16 has been described in conjunction with the operation of a welder circuit, it is equally adapted to use with any circuit in which it is desirable to obtain only full half cycles of current flow through the controlling electronic tube.

While certain preferred embodiments of the invention have been specifically disclosed, it is understood that the invention is not limited thereto, as many variations will be readily apparent to those skilled in the art and the invention is to be given its broadest possible interpretation within the terms of the following claims.

What is claimed is:

1. In a control circuit, an electronic tube having an anode, a cathode, and at least a pair of auxiliary electrodes, means for applying a first alternating voltage between said anode and cathode, means for applying a second alternating voltage displaced in phase from said first voltage between one of said auxiliary electrodes and said cathode such that said one auxiliary electrode is positive when said anode begins to go positive but negative shortly thereafter, initiating means, voltage establishing means between said cathode and other auxiliary electrode for preventing conduction of said tube until after the operation of said initiating means, means for dissipating the effect of said last mentioned means after the operation of said initiating means whereby said tube will begin conducting only during the period in which both said anode and said one auxiliary electrode are positive, and control means responsive to current flow through said tube.
2. In a control circuit, an electronic tube having an anode, a cathode, and at least a pair of

auxiliary electrodes, means for applying a first alternating voltage between said anode and cathode, means for applying a second alternating voltage displaced in phase from said first voltage between one of said auxiliary electrodes and said cathode which tends to make said tube become conductive during a predetermined initial portion of a positive half cycle of anode voltage and which prevents conduction of said tube during the remainder of the positive half cycle, voltage establishing means between said cathode and other auxiliary electrode preventing conduction of said tube, initiating means, means for dissipating the effect of said voltage establishing means after the operation of said initiating means whereby said tube will begin conducting only during said predetermined portion of a positive half cycle of anode voltage and control means responsive to current flow through said tube.

3. In a control circuit, an electronic tube having an anode, a cathode, and at least a pair of auxiliary electrodes, means for applying a first alternating voltage between said anode and cathode, means for applying a second alternating voltage displaced in phase from said first voltage between one of said auxiliary electrodes and said cathode such that said one auxiliary electrode is positive when said anode begins to go positive but negative shortly thereafter, means for establishing a direct voltage between said other auxiliary electrode and said cathode whereby said other electrode is normally negative to said cathode during those periods in which said anode is positive, an initiating switch, means for dissipating said direct voltage after operation of said initiating switch whereby said tube will begin to conduct only during the period in which said one auxiliary electrode and said anode are both positive, and control means responsive to current flow through said tube.

4. In a control circuit, an electronic tube having an anode, a cathode, and control and shield grids, means for applying a first alternating voltage between said anode and cathode, means for applying a second alternating voltage displaced in phase from said first voltage between said cathode and shield grid such that said shield grid is positive when said anode begins to go positive but negative after said anode has been positive for a short interval, initiating means, means for establishing a direct voltage between said cathode and control grid for preventing conduction of said tube until after operation of said initiating means, means for eliminating the effect of said last mentioned means after the operation of said initiating means whereby said tube will begin to conduct only during the interval when both said anode and shield grid are positive, and control means responsive to current flow through said tube.

5. In a control circuit, an electronic tube having an anode, a cathode, and control and shield grids, means for applying a first alternating voltage between said anode and cathode, means for applying a second alternating voltage displaced in phase from said first voltage between said cathode and shield grid such that said shield grid is positive when said anode begins to go positive but negative after said anode has been positive for a short interval, a capacitor, means connecting said capacitor to said control grid, means for charging said capacitor with a polarity such that said control grid is negative with respect to said cathode when said anode is positive, an initiating switch, means for dissipating the charge upon

said capacitor after the operation of said initiating switch whereby said tube will begin to conduct only during the interval when both said anode and shield grid are positive, and control means responsive to current flow through said tube.

6. In a control circuit, an electronic tube having an anode, a cathode, and control and shield grids, means for applying a first alternating voltage between said anode and cathode, means supplying a second alternating voltage displaced 180 degrees from said first voltage, a first series circuit including a first resistor and a first capacitor connected across said second voltage, means connecting said cathode to the terminal of said first capacitor spaced from said first resistor, means connecting said shield grid between said first resistor and said first capacitor, whereby said shield grid voltage is displaced in phase from said first and second voltages an amount such that said shield grid is positive when said anode begins to go positive but negative after said anode has been positive for a short interval, a second series circuit including a second resistor, a second capacitor, the control grid and the cathode connected across said second voltage, whereby said second capacitor is charged during positive half cycles of said second voltage, the charge upon said second capacitor making the control grid negative at all times when the anode is positive, an initiating switch in parallel with that part of said second series circuit which includes said second capacitor, the control grid and the cathode whereby recharging of said second capacitor is prevented after operation of the initiating switch, means for dissipating the charge upon said second capacitor after operation of the initiating switch whereby the tube will begin to conduct only during the interval when both the anode and shield grid are positive, and control means responsive to current flow through the tube.

7. In a control circuit comprising an electronic tube and means responsive to the conduction thereof; an electronic tube having an anode, a cathode, and at least a pair of control electrodes; means for applying a first alternating voltage between said anode and cathode, initiating means, means for applying a direct voltage between one of said control electrodes and said cathode which prevents conduction of said tube, means for dissipating the effect of said last mentioned means upon operation of said initiating means, and means for applying a voltage between said other control electrode and said cathode which makes said other control electrode positive with respect to said cathode as said anode becomes positive and which makes said other control electrode negative with respect to said cathode a small fraction of a half cycle after said anode has become positive, whereby said tube can begin to conduct only during the initial portion of a half cycle.

8. In a control circuit comprising an electronic tube and means responsive to the conduction thereof, an electronic tube having an anode, a cathode, and at least a pair of control electrodes, means for applying a first alternating voltage between said anode and cathode, means supplying a second alternating voltage displaced substantially 180 degrees from said first voltage, a first series circuit connected across said second voltage including a first resistor and the first capacitor, means connecting said cathode to the terminal of said first capacitor spaced from said

first resistor, means connecting one of said control electrodes between said first resistor and said first capacitor whereby the voltage between said one control electrode and said cathode is displaced in phase from said first and second alternating voltages an amount such that said one of said control electrodes is positive when the anode begins to go positive but negative after said anode has been positive for a small portion of a half cycle; a second series circuit connected across said second alternating voltage including a second resistor, a second capacitor, the other of said control electrodes and said cathode; said second capacitor being charged during positive half cycles of said second alternating voltage, said 15 other control electrode being made negative when said anode is positive by said charge on said second capacitor; an initiating switch in parallel

5 with that part of second series circuit which includes said second capacitor, the other of said control electrodes and said cathode, whereby recharging of said second capacitor is prevented after operation of said initiating switch; and means for discharging the charge upon said second capacitor after operation of said initiating means whereby the tube will begin to conduct only during the interval when both the anode 10 and said one control electrode are positive.
